M. H. SPIELMAN.
CIGAR LIGHTER.
APPLICATION FILED MAY 5, 1916.

1,272,869.

Patented July 16, 1918

Max H. Spielman Inventor
By his Attorney Isaac B. Owners

UNITED STATES PATENT OFFICE.

MAXIMILLIAN H. SPIELMAN, OF NEW YORK, N. Y.

CIGAR-LIGHTER.

1,272,869.

Specification of Letters Patent. Patented July 16, 1918.

Application filed May 5, 1916. Serial No. 95,571.

To all whom it may concern:

Be it known that I, MAXIMILLIAN H. SPIELMAN, a citizen of the United States, and a resident of borough of Manhattan, 5 county, city, and State of New York, have invented certain new and useful Improvements in Cigar-Lighters, of which the following is a description in such full, clear, and exact terms as will enable any person 10 skilled in the art to which it pertains to make and use the same.

My invention relates to improvements in cigar lighters and other devices which are supplied with an electrical current through 15 a flexible cable running in and out from a reel through parts of which the electrical circuit is passed.

In such devices difficulty has been experienced from short circuiting due to the 20 wearing away of the insulation of the flexible electrical cable. Such short circuits result in danger from fires not to speak of complete inoperativeness of the device and my invention involves various improvements 25 which will be fully set forth hereinafter by which these short circuits are safeguarded against.

The invention involves other features all 30 of which will be fully set forth hereinafter and pointed out in the claims.

Reference is had to the accompanying drawings in which—

Figure 1 is a sectional elevation of the reel device.

Fig. 2 is a section on the line 2—2 of Fig. 1.

Fig. 3 is a section on the line 3—3 of Fig. 1.

Figs. 4 and 5 are detailed views showing 40 the operation of the automatic circuit breaking device.

Fig. 6 is a fragmentary elevation showing the reel adjusting arbor.

Fig. 7 is a detailed section showing a 45 modification of the circuit breaker device.

Fig. 8 is a detailed section showing a modification of the switch to the reel.

The invention is here illustrated in connection with an incandescent cigar lighting 50 device 10 but it should be understood that it is applicable to any other electrical device

supplied with current by a back and forth moving member such as the flexible conducting cable or encoiled wires 11.

12 is a box or casing in which the reel 55 parts are contained and which is adapted to be fastened to any suitable stationary part. This box has spring holder fingers 14 for the lighting device 10 and a push button 15 which is adapted to be engaged by the 60 lighting device when the lighting device is held by the fingers 14 thereby moving the push button back into the case.

The terminals of the cable 11 are in electrical connection respectively with disks 16 65 and 17 on the reel and said disks, of course, are insulated from each other. One branch of the circuit passes off to a binding post 18 by a spring arm 19 fastened to the binding post 18 at its rear end and carrying at its 70 forward end an L-shaped contact finger 20 one arm of which is engaged by the button 15 and the other arm of which is normally in contact with the disk 17 thereby completing the current to one of the wires in 75 the cable 11.

But when the lighter 10 is placed in position between the spring fingers 14 it pushes back the button 15 this button being in engagement with the other arm of the L- 80 shaped contact finger 20, pushes the same inward and moves the other arm thereof away from the disk 17 and out of contact therewith thus breaking the circuit. The result is that the circuit is broken and the 85 cable or conducting wires 11 are not charged with the current at all times during which the lighting device 10 is in inactive position between the fingers 14. Hence when the device is not in use the circuit is broken and the 90 danger of short circuits through defective insulation is avoided.

It is desirable, however, to reduce this danger of short circuiting to the uttermost minimum and in doing this I provide a 95 spring finger 22 which carries the current of the second binding post 23 with a peculiar circuit breaker acting against the flange 16 of the reel. This circuit breaker is shown in detail in Figs. 4 and 5. The 100 object is to have the circuit breaker close the circuit when the wire 11 is being drawn

out but to break the circuit the instant that the wire returns its movement or very shortly after that instant.

In attaining this end the circuit breaker 5 comprises a star shaped contact wheel 24 mounted to rotate on the free end of the arm 22 and fastened to and turning with a non-conducting cam 25 having two eminences. These eminences of the non-conducting cam 25 and the prongs of the star wheel 24 are adapted to coöperate with a notch or tooth like formation 26 in the face of the reel flange disk 16. The number of these prongs or teeth determines the length of the cable 10 that may be pulled out before the circuit breaker registers and the length at which the circuit is broken on return. Now the parts are so arranged that when the reel is turning to pay out the cable 11 the star wheel stays in contact with the disk 16 and the circuit is closed so that the cigar lighter may be used. This position is shown in Fig. 4 where the disk 16 is supposed to be turning in the direction of the arrow. As soon as 15 the user has finished lighting the cigar, however, and allows the cable 11 to run back into the housing 12 the reel disk 16 reverses its movement as in Fig. 5 and the star wheel 24 co-acting with the tooth cavity 26 reverses 20 its movement until the insulation cam 25 runs into engagement with the flange and lifts the conducting star wheel 24 out of contact with the disk thereby breaking the circuit. Now when the disk 16 continues 25 to run in the direction of the arrow shown in Fig. 5 the tooth cavity 26 will move idly by the insulation cam 25 and will not return the star wheel 24 into contact with the disk 16. But when the disk reverses its motion 30 to pay out the cable 11 the tooth cavity 26 will run into the right hand eminence of the cam 25 and impart a partial rotation to the cam and star wheel which restores the star wheel to contact with the disk. This 35 operates the cigar lighter. It will be noted that the eminences of the cam 25 are of unlike form so that one serves to rotate the star wheel into contact while the other is not affected by the tooth cavity 26 but holds the 40 star wheel out of contact with the reel disk. This results in passing the electrical current through the reel and cable devices only during the instant that the cigar lighter is being employed and cuts the circuit out at all 45 other times.

The reel of the cable 11 is operated in the usual way by spring 27 of an arbor 28 and the tension of the spring may be regulated by inserting a screw driver into the slot 29 50 in the head 30 of said arbor. 31 is a spring which acts against the walls of ratchet-notch 32 in the arbor head 30 holding the arbor and the spring 27 at the desired position.

From the aforesaid it will be noted that 55 every precaution is taken to avoid the pres-

ence of the current in the moving parts of the device except during the period that the cigar lighter or other electrical device is actually in use and in this way the danger of leakage through defective insulation and other abnormal conditions is completely avoided.

If desired the push button 15 may be dispensed with and one of the spring fingers 14^a as shown in Fig. 8 arranged loosely in the casing 12 and fastened directly to a contact elbow so that when the electrical device 10 is engaged between the fingers the finger 14^a is moved so that the contact finger 20^a is pressed back out of contact with the 80 disk 17.

Fig. 7 shows a modification in the star wheel 24^a in which the insulation cam 25^a is fastened in an opening in the periphery of the star wheel and projects beyond the same tangentially in such a fashion as to have the same characteristic operation as the device illustrated in Figs. 4 and 5.

I claim:—

1. The combination with an electrical device and a two part flexible conductor for supplying electric current thereto, of a reel for winding the conductor, said reel having two insulated contact members, a pair of electric current supply terminals, means for forming an electrical connection between one of the said contact members and one of the terminals, a spring contact finger for conducting current from the other terminal to the other contact member, said contact finger being provided with a conducting rotary part which is provided with an insulation segment on its periphery, said rotary part engaging the corresponding contact member, the said contact member being provided with means for positively engaging the said rotary part to periodically turn the same.

2. The combination with an electrical device and a two part flexible conductor for supplying electric current thereto, of a reel for winding the conductor, said reel having two insulated contact members which are electrically connected to the respective parts of the conductor, a pair of electric current supply terminals, means for forming an electrical connection between one of said contact members and one of the terminals, a spring contact finger for conducting current from the other terminal to the other contact member, a toothed wheel journaled on said contact finger and adapted to be rotated by the reel, the contact member being provided with a projection for positively engaging the toothed wheel to rotate the same.

3. The combination of an electrical device, a cable connecting it with the source of energy, a reel over which the cable is wound, a contact surface on the reel and in the circuit, a spring finger in the circuit and a toothed conducting wheel mounted on the 130

finger and having an insulation section for the purpose specified, the wheel engaging the said contact surface and such surface having an irregularity thereon, to engage the 5 toothed wheel and rotate it back and forth by the back and forth rotation of the reel, whereby to make and break the circuit.

In testimony whereof I have hereunto signed my name in the presence of two witnesses.

MAX H. SPIELMAN.
